UNITED STATES PATENT OFFICE.

MILTON C. STERN AND FRANK E. PFEIFFER, OF DAYTON, OHIO, ASSIGNEES TO THE EGORY REGISTER COMPANY, OF DAYTON, OHIO, A CORPORATION OF OHIO.

AUTOGRAPHIC REGISTER.

Original application filed March 12, 1923, Serial No. 624,515. Divided and this application filed June 5, 1924. Serial No. 717,950.

Our invention relates to autographic registers and is a division of our copending application filed March 12, 1923, Ser. No. 624,515.

5 It is the object of our invention to provide an autographic register which shall be inaccessible in its interior to anyone, save the person possessing the master key for unlocking the register.

10 It is the additional object of our invention to provide means for locking the cover plate and carbon container as a unit with the register body, through the medium of this same key and lock which permits access to the interior of the autographic register, thus preventing tampering with the carbons and the consequent opportunity for making an autographic record on the top sheet, without making suitable and corresponding entries on the sheets below for the purpose of perpetrating frauds.

15 It is the additional object of the invention to provide a means of supporting the carbon copy and the supply thereof, so that fresh supplies may be quickly and readily inserted and then locked in position.

20 It is also an object to provide means of maintaining the tension on the carbon paper to prevent its movement until desired.

25 Referring to the drawings, our invention is illustrated as follows:

Figure 1 is a front elevation of the assembled autographic register casing and cash drawer.

30 Figure 2 is a side elevation of Figure 1, looking at Figure 1 from the right hand side.

35 Figure 3 is a section of the casing of the register proper, taken on the line 3-3 of Figure 1, looking in the direction of the arrow.

40 Figure 4 is a section on the line 4-4 of Figure 1, looking in the direction of the arrows.

45 Figure 5 is an elevation of the carbon roll support, looking in the direction of the arrow 5 of Figure 8, showing the cover removed.

50 Figure 6 is a section on the line 6-6 of Figure 2.

Figure 7 is a section of the carbon supply mechanism and an end elevation of the no sale key mechanism. This section is taken on the line 7 of Figure 2.

55 Figure 8 is an end view of the carbon supply container and also an end elevation of the no sale key mechanism with the register cover and casing in section, taken on the line 8-8 looking in the direction of the arrows in Figure 2.

60 Figure 9 is a plan view of the guiding rollers and the paper supply reel.

Figure 10 is a view in section on the line 10-10 of Figure 9 of the paper supply roll, of which there may be any desired number.

65 Figure 11 is a detail of the universal connection of the guide roller with the supporting side wall and retaining member in section.

70 Figure 12 is a plan view with the support in section of the universal joint connection between the guide roller and its support. This view is taken on the line 12-12, looking in the direction of the arrows of Figure 9.

75 Figure 13 is an elevation of the universal joints of the guide rollers, with the retaining cover removed, looking in the direction of the arrow 13 in Figure 12.

80 Referring to the drawings: 1 represents a base frame of a drawer casing, which has side walls 2 and 3 and a rear wall 4. The casing is provided with a top 5, upon which is mounted and securely fastened our improved autographic register.

85 The autographic register mounted upon the top 5 has a base 6, a front wall 7, a side wall 8, and a second side wall 9, a pivoted rear wall 10, and a cover 11.

90 The cover 11 may have one or more writing openings 12, beneath which appears the top autographic sheet 13.

95 A handle 14 is used to deliver the sheet or sheets of paper from the machine, and to wind a record roll, if that is desired. It will be understood that any form of delivery of the sheets may be utilized and the detailed method of delivery forms no part of our invention.

100 In Figure 4 a gear 15, with teeth 16, is shown mounted on the shaft 17, to which the handle 14 is attached. This pin wheel or gear 15 is utilized for delivering the sheets of paper out of the machine by the engagement of the pins 16 with perforations in the margins of the sheets. According to customary practice there is a pin wheel on either side of the register, having its pins

engaging with perforations in either margin of the paper.

Referring to the method of supplying carbon to the autographic register, I have provided a swinging casing 18, which is held in position by a lug 19 on the cover 11 being inserted into an opening 20 in the casing 18, so that when the cover 11 is locked in position in the top of the casing 18 it cannot swing open.

However, when the lug 19 is withdrawn from the opening 20, the casing 18 can swing about the pin 21, which is held in the bracket 22 mounted on the wall 8, thus permitting access to the carbon roll 23, which is mounted on a spindle 24. The plurality of sheets of the carbon roll are conveyed transversely to the writing table and interleaved between the sheets of which 13 is the top sheet in a manner well known in the art.

In Figures 5 and 6 the details of this suspension of the carbon roll will be seen. The spindle 24 is suspended in a pair of jaws 25 carried by the side wall 8. The other end 26 of the spindle is supported pivotally at 27 on the bracket 22.

A spring 28 working against a washer 29 and a plate 30 serves to keep the roll 23 from unwinding.

It will be understood that the carbon sheets are held in position on the other side of the register adjacent to the wall 9 by any desired means familiar in the art. Thus 23 it is possible to swing open the carbon roll casing and swing the supporting shaft outwardly for the easy insertion of the roll on this supporting shaft or spindle 24.

Referring to the means for guiding the leaves of paper or sheets of paper, such means being shown in Figures 9, 11, 12 and 13, 31 designates guiding rollers each having a projecting end 32 located in a slot 33 in one of the side walls. A similar projection 45 at the other end of the roller 31, as at 34, projects into a portion of the wall on the opposite side. The member 34 has a ball shaped head 35 working in the socket or cutaway portion 26. The socket 36 is large 50 enough to contain the head 35, but the head 35 is too large to pass through a slot 37, which communicates with 36 and through which 34 is adapted to pass.

After the head 35 has been put in the socket 36 a retaining plate 38 is fastened by the screws 39 to the side wall of the register to thus complete the ball and socket joint.

When it is desired to lift up the rollers 60 to facilitate the threading of the paper strips, this may be done without completely upsetting the roller or loosening it, a matter of considerable advantage.

The paper rolls are supported as follows: 65 A roller, such as illustrated in Figure 10,

designated 40, having on one end a stub shaft 41, which fits into a cutaway portion 42 in the boss 43 on the side wall 8 of the register.

On the opposite wall 9 of the register is 70 a similar raised portion 44 with a slot 45 cut therein, so that a stub shaft 46 carried by the other end of the roll 40 may rest therein to cooperate in supporting the roll.

75 The stub shaft 46 is adapted to slide transversely in the roll 40, but is forced outwardly by a spring 47 in the spring chamber 48. One end of the spring abuts against one end of the chamber and the other end against the head 49 on the shaft 46. This head also comes in contact with a guide or filler 50 in the chamber 48. The end plate 51 on the roll 40 prevents the 80 exit of the filler 50.

85 The members 44, with the slots 45, are connected together by an arch shaped member 52 to assist in guiding the roller shafts into the slots 45. These slots are at an angle to the vertical.

90 In registers of this type adapted to be used with cash drawers it is essential that access to the interior of the same may not be had except by a certain person or persons, as the case may be. To that end I 95 have provided a lock 53. When the same is locked the interior of the register is inaccessible to anyone, but when it is unlocked by some one having the master key the plate 10 can be opened on its pivot 54 100 to permit access to the mechanism within the register.

105 This lock 53 also controls the means for locking the cover plate and carbon containers as a unit with the register body which prevents tampering with the carbons and the consequent opportunity for making an autographic record on the top sheet, without making suitable and corresponding entries on the sheets below for the purpose of 110 perpetrating frauds.

115 It will be understood that we comprehend within our invention various modifications in which our invention may be embodied.

Having thus fully described our invention, what we claim as new and desire to secure by Letters Patent, is:—

1. In an autographic register, a register casing consisting of the bottom, side walls and end walls, a supplementary casing to 120 contain a carbon roll, said casing being located on the exterior of one of said side walls and pivotally mounted thereon, a cover for said register casing, and means on said cover to engage with the supplementary 125 casing to lock the whole together as a unit.

2. In an autographic register, a register casing consisting of the bottom, side walls, and end walls, a supplementary casing to 130 contain a carbon roll, said casing being lo-

cated on the exterior of one of said walls and pivotally mounted thereon, a cover for said register casing, means on said cover to engage with the supplementary casing to lock the whole together as a unit, a carbon roll support in said supplementary casing pivotally mounted on the side wall at one end and supported at the other end by a projection from the side wall, and means on the swinging supplementary casing to lock said carbon roll support in an engagement with the supporting means on the side wall of the casing when the parts are in their closed position.

15 3. In an autographic register, a register casing consisting of the bottom, side walls, and end walls, a supplementary casing to contain a carbon roll, said casing being located on the exterior of one of said walls, and pivotally mounted thereon, a cover for said register casing, means on said cover to engage with the supplementary casing to lock the whole together as a unit, a carbon roll support in said supplementary casing pivotally mounted on the side wall at one end and supported at the other end by a projection from the side wall, a means on the swinging supplementary casing to lock said carbon roll support in an engagement with the supporting means on the side wall of the

casing when the parts are in their closed position, means on carbon roll support for yieldingly resisting the movement of the carbon paper thereon.

4. An autographic register, having side walls, a guiding roller mounted in said side walls, one end of said guiding roller being located freely in a slot in the wall and the other end of the roller being located in a socket in the other wall, a ball on the end of said roller adapted to be placed in said socket, said socket being considerably larger than said ball, and means for sealing the enlarged area of said socket to prevent the removal of one end of the roller and permit the free movement of the ball in said socket.

5. An autographic register having side walls, a plurality of rollers for guiding the sheets of material used in said register, each of said rollers having one end fitting in a slot in one side wall and a ball loosely fitting in a socket in the other side wall, and means to retain the ball in the socket whereby the rollers may turn freely in their operative position and have one end swing up in a plane vertical to the side walls.

In testimony whereof, we affix our signatures.

MILTON C. STERN.

FRANK E. PFEIFFER.
